UNITED STATES PATENT OFFICE.

ROSWELL WAKEMAN, OF PORT DEPOSIT, MARYLAND.

IMPROVEMENT IN PRESSES.

Specification forming part of Letters Patent No. 31,841, dated March 26, 1861.

To all whom it may concern:

Be it known that I, ROSWELL WAKEMAN, of Port Deposit, in the county of Cecil, in the State of Maryland, have invented new and useful Improvements in Presses for Baling Hay, Hemp, and Cotton; and I do hereby declare that the following is a clear and exact description of the same, reference being had to the accompanying drawings, making a part of this specification, in which—

Figure 1 shows an end elevation with the arrangement of the windlass and pulleys. Fig. 2 represents a side view of the press with the sides and top open for discharging the bale.

My invention consists in having double trapdoors to form the top of the press, which, when opened to receive the hay or other substances to be pressed, leave the space clear to be filled or the bale to be discharged on either side, and when the doors are closed they are firmly secured to resist the pressure by a cross-bar, it being placed under a yoke and spring held by rods, to which the pulleys are attached, so that all of the pressure is brought to bear directly upon the substance being pressed.

To enable others skilled in the art to make and use my invention, I will describe it more fully, referring to the drawings and the letters marked thereon.

The same letters indicate like parts in both of the figures.

The frame and timber work may all be light, the base A being framed together in the usual manner to form the support for the ends B B, which only require to be of plank from one and one-half to two inches in thickness for the largest presses. The pieces C C are also of plank, and are pinned or spiked to the ends B B on the outside, so as to form ribs to brace and support the pressure outward. On the top of the pieces C C are cap-pieces D D, which form the support for the yoke a a, the springs b b, and a guide for the rods c c. Through the upright and plank B B is a slit or long mortise, E, to allow the timber F free play to slide up or down. On the top of this timber are secured short pieces of plank d d d d, which make the platform and follower. On each end of the timber F is a strap of iron, e e, bent so as to form a stirrup, which supports the platform and elevates it when pressing. The straps e e are the blocks in which the sheaves

or pulleys f f are secured. To the timber F, outside of the ends B B, are strong staples g g, into which a rope or chain is fastened, it passing up over other pulleys, h h, which are suspended on two rods, c c, that pass through the cap-pieces D D and extend above the top sufficient length to form a stirrup by a yoke, a a, extending over the two, and holds to its place a bow-spring, b b, which operates to liberate the cross-bar a when the rope is slackened, so that it is free to take out and replace. The rope passing around the pulleys f f and over h h, and extending down to the windlass H, makes a complete tackle, so that the power applied to the lever I, acting upon the ratchet-wheels J J, and retained by the stationary pawls j j, a large amount of force and pressure is obtained in a very easy manner, and a bale can be more closely packed in less time and with less power by this arrangement than by any other machine now in use that is operated by hand-power, for the reason that every ounce of power applied operates directly on the top and bottom of the substance to compress it, and there is no strain on the frame or any part of it, except the draft upon the windlass, which need not be more than one pound to fifty of the pressure on the bale.

It has been my great object and study to construct a simple, efficient, cheap, light, and portable hay-press—one that can be taken into the meadows and the hay put into bales as soon as it is well cured. A saving of at least fifty per cent. in quality and quantity is effected by not exposing it to the weather in handling it loosely after it is once cured and stacked or settled in the mow. All hay for market should be baled when fresh made.

Fig. 2 shows the press in the position it is left after the bale is discharged. To operate, the turn-up doors K K, which are hinged to the frame by the bars k k, are closed up and secured by the hooks l l. The platform F is lowered to the bottom by its own gravity, when the windlass is released by raising the pawls j j from the ratchet-wheels J J, thereby giving the advantage of all of the inner space to be occupied by the material. The strips for binding are first laid on the platform, and the box is filled up with the material to be baled. The hinged trap-doors M M on the top are then closed down upon it, and the cross-bar G is inserted, each end being under the springs

b b and yoke *a a*, which are free to be raised a foot or more, if necessary. Then, by applying the lever-power to the windlasses, the work is effectually accomplished.

I do not claim the pulleys, windlass, ratchet-wheels, and pawl-levers for compressing substances into bales; but

What I do claim, and desire to secure by Letters Patent, is—
The arrangement of the double trap-doors,

being secured by a cross-bar, held at the ends under yokes or stirrups, in combination with springs, sliding rods, pulleys, and windlasses operating on both ends of the moving platform, substantially as described, and for the purposes herein set forth.

ROSWELL WAKEMAN.
